UNITED STATES PATENT OFFICE.

EDWARD LEICHTER, OF NEVADA CITY, CALIFORNIA, ASSIGNOR OF ONE-HALF TO JAMES C. CAMPBELL, OF NEVADA CITY, CALIFORNIA.

ROCK-DRILL.

No. 853,555.

Specification of Letters Patent.

Patented May 14, 1907.

Application filed June 20, 1906. Serial No. 322,562.

To all whom it may concern:

Be it known that I, EDWARD LEICHTER, a citizen of the United States, residing at Nevada City, in the county of Nevada and State of California, have invented new and useful Improvements in Rock-Drills, of which the following is a specification.

My invention relates to power driven drills and especially to rock drills of the Ingersoll or Sargent type. Its object is to provide a drill of few parts which will be strong, practical and durable; which will provide means for adjusting and maintaining in adjustment the cylinder on the shell; which will operate the valve by direct pressure from the cylinder in contradistinction to the usual exhausted valve motion; and which will have a novel means of balancing the control valve and permit a ready renewal of the wearing parts without having to discard the whole valve.

The invention consists of the parts and the construction and combination of parts as hereinafter more fully described and claimed, having reference to the accompanying drawings, in which—

Figure 1 is a longitudinal sectional view. Fig. 2 is a transverse section. Fig. 3 is a detail view of the valve.

1 represents my cylinder which has its bore turned larger at one end than at the other, and 2 is a double piston turned down in the middle as shown at 3 and having its smaller end fitting the smaller end of the cylinder and its larger end fitting the enlarged portion of the bore of the cylinder.

The rear end of the piston engages with the rifle bar 4 in the usual manner, and the front end carries the piston rod 5. The front end of the piston rod is provided with the usual chuck 6.

The two ends of the cylinder are made with tapered seats to receive the correspondingly tapered ends of the respective front and rear heads 7—8. The rear head carries the usual ratchet mechanism 9 for imparting, through the medium of the rifle bar 4, an intermittent rotative movement to the drill.

A split bonnet 10 is adapted to fit over the drill rod and the end of the front head 7. This bonnet 10 serves to hold in place and to compress the crimp or packing 11, which is placed around the piston rod to maintain a tight joint. A split washer 12 may be insert-

ed up against this crimp to compress it endwise.

The rear head 8 is inclosed by a bonnet 13 which houses the spring 14 which abuts against the rear head 8 and holds the latter to its seat. The front bonnet 10 and the rear bonnet 13 are connected by the usual side rods 15. Sufficient play is provided for the sliding movement of the rear bonnet on its seat on the rear end of the cylinder, to allow for the absorbance of shock by the spring 14.

The cylinder has lateral guide projecting flanges 16 which seat on the shell 17; this shell 17 is made with the longitudinally extending side flanges 18, and a suitable space is left on each side of the cylinder between the ends of the flanges 16 and the flanges 18 for the interposition of the adjusting strips 19. These strips 19 are adapted in the first place to seat as snug as possible between the flanges 18 and the flanges 16, but are transversely slotted as at 20 so that as wear takes place shims of suitable thickness may be interposed between one or both of the adjusting strips and a corresponding flange 18. The cylinder is thus held against lateral movement, but is freely slideable lengthwise in the channels formed by the strips 19, brace flanges 18 and the clamp strips 21 and clamp bolts and nuts 22. The feed of the drill to the work is done by the feed screw 22' which is mounted on the shell and engages a feed nut 22^a on the cylinder.

The use of the transversely slotted adjusting strips permits every bit of wear between the shell and cylinder to be taken up, and thereby prevents side shake of the cylinder on the shell.

The drill piston is reciprocated through the medium of a suitable fluid, such as compressed air admitted alternately to each end of the cylinder through the ports 23. The admission of the motive fluid is controlled by a valve of special design, located in the valve chest 24.

A double-ended piston 25 operates in the valve chest and the two piston ends are connected by a ring portion 26, which is adapted to slip over the valve member 27. This valve member has a D-face adapted to bring one or the other of the inlet ports 23 and the exhaust port 28 into register. The valve is

made hollow and is surmounted and held snug to its seat by a ring 29 which rests on the ring 26 and has a snug sliding fit with the underside of the removable chest plate 30.

5 The motive fluid from any suitable source of supply is admitted through port 31 to the valve chest and is allowed to circulate freely on the outside of the valve proper, so that the valve practically remains in balance and 10 the motive fluid which is admitted alternately to each end of the chest to move the valve, has only the weight of the valve and the friction of the parts within the chest to contend against. Whatever leak there may 15 be around the top of the ring 29, finds a ready outlet through the exhaust 28. By using ring packing, as this construction permits, there is practically no leak around the pistons.

20 The ends of the chest are closed by the removable plugs 31^a.

The fluid to operate the piston valve is admitted alternately to each end of the chest through one or the other of the parts 32—33 25 which connect at each stroke of the piston 2 with a respective live air chamber at an end of the cylinder A.

Exhaust from the ends of the valve chest 24 takes place whenever a port 32 or 33 is 30 brought into communication with the central annular passage-way 3; the latter having the exhaust outlets 34.

The operation of the piston valve and of the drill piston is as follows: With a suitable 35 fluid under pressure entering through port 31 and circulating about the valve, and with the valve moved into position to allow live air to enter the cylinder through one or the other of the ports 23, the drill piston 2 is 40 made to traverse its chamber until one or the other of the ports 32—33, according to which direction the piston 2 is traveling, is uncovered. Assuming piston 2 to be traveling to the left, the port 32 will be uncovered 45 to put it in communication with the source of live air supply; while the port 33 will be open to the exhaust through the passage 3 and ports 34—28. The live air entering port 32 passes to the left end of the chest and 50 operates to move the piston valve 25 and allow the exhaust to take place from the front end of the cylinder A and to admit live air to the rear end of the cylinder. As soon as the piston 2 has about completed its forward 55 stroke, the port 32 is open to the exhaust and the port 33 is thrown into communication with the live air pressure in the rear end of the cylinder and the piston valve is reversed in the proper manner.

60 In all valve constructions for rock drills, of which I have knowledge, there has been

danger of leakage around the valve due to wear, which will often result in the valve being brought to such a state of balance that it will stick and refuse to move. This difficulty is entirely obviated in my construction, since the likelihood of leakage is reduced by the use of ring 29 and the hollow valve 27 and the employment of ring packing on the piston 25. At the same time my piston 70 valve is worked under the full effective pressure of live air in the cylinder. By increasing the diameter of the cylinder bore at the front end of the cylinder I am enabled to insure a sufficient pressure always being 75 brought on the piston 2, to pull the drill out of the hole; a not infrequent difficulty heretofore has been the trouble arising from the sticking, binding or pinching of the drill in the drill hole. By my construction of enlarging the front end of the chamber, I make 80 up for the displacement by the rod 5. By making the two ends of the cylinder and the front and rear heads 7 and 9 with corresponding tapered seats, it allows the parts to open 85 up in case the piston bumps the front head, and the out-blowing air will clear the seats of all grit and dirt; thus cleaning themselves and allowing them to seat snug when the piston reverses its movement. With drills 90 using square seats for the cylinder and heads there has always been difficulty arising from leaks around the abutting parts.

Having thus described my invention, what I claim and desire to secure by Letters Patent is—

A rock drill having in combination a cylinder with tapered seats at the ends, a piston, front and rear heads having corresponding conical portions to fit said seats, the rear end 100 of said cylinder having an extension beyond the adjacent seat, a chambered bonnet 105 enclosing the rear end of the cylinder and receiving said extension and having a limited sliding movement relative thereto, a spring 110 within the chamber of said bonnet and abutting against the rear head, a bonnet fitting the front end of the cylinder fitting over the drill rod and the end of the front head, and tie rods connecting the two bonnets to hold 115 the heads to their seats on the cylinder, said seats and the conical ends of the heads forming loose joints and permitting the heads to give in case they are struck by the piston, and to reseat themselves.

In testimony whereof I have hereunto set my hand in presence of two subscribing witnesses.

EDWARD LEICHTER.
